[57] CLAIM

The ornamental design for a beach towel with inflatable pillow and foam body mat inserts and interior storage pockets, as shown and described.

DESCRIPTION

FIG. 1 is a front elevational view of the beach towel with inflatable pillow and foam body mat inserts and interior storage pockets showing my new design;

FIG. 2 is a rear elevational view thereof;

FIG. 3 is a right view thereof;

FIG. 4 is a left view thereof;

FIG. 5 is a top plan view thereof;

FIG. 6 is a bottom plan view thereof; and,

FIG. 7 is an exploded isometric view thereof illustrating the inflatable foam pillow and body mat inserts and the location of the interior pockets.
